UNITED STATES PATENT OFFICE.

AUGUSTE J. LECOUTRE, OF WORCESTER, MASSACHUSETTS, ASSIGNOR TO ROYAL WORCESTER CORSET CO., OF WORCESTER, MASSACHUSETTS, A CORPORATION OF MASSACHUSETTS.

CORSET-STEEL.

1,244,060.

Specification of Letters Patent. Patented Oct. 23, 1917.

Application filed April 12, 1917. Serial No. 161,597.

To all whom it may concern:

Be it known that I, AUGUSTE J. LECOUTRE, a citizen of the United States, residing at Worcester, in the county of Worcester and State of Massachusetts, have invented certain new and useful Improvements in Corset-Steels, of which the following is a specification.

My invention relates to corset steels, and more particularly to the clasps or fastening devices which attach the two front corset steels together.

The object of my invention is to provide corset clasps of such construction that tilting of the plate steel stud members of the clasps will be largely prevented when the corsets are in use and under tension on the wearer, thus avoiding that annoying pinching of the flesh of the wearers, such as is likely to occur with the corset clasps at present in use. To this end the studs on the plate steel stud members of the clasps are formed with conical heads between which and the said steel stud members said studs are constructed with short straight or cylindrical necks or stems of a length, when the said stud members are covered with cloth, about equal to the thickness of the slotted eyes or eye members on the other plate steel members of the clasp.

Referring to the drawing:

Figure 1 is a front view of the two steels, and the clasps or fastening devices, having studs of my improved construction.

Fig. 2 is a side view of the steel shown at the right in Fig. 1, detached, looking in the direction of arrow *a*, same figure.

Fig. 3 is a section, on line 3, 3. Fig. 1, looking in the direction of arrow *b*, same figure.

Fig. 4 shows, on an enlarged scale, one of the studs inserted through an opening in one of the steels, which is shown in cross section, before the stud is headed.

Fig. 5 corresponds to Fig. 4, but shows the lower end of the stud headed or spread, to secure the stud in the opening in the steel.

In the accompanying drawing, 1, and 2 are the two front steels of a corset; they may be of the usual form, and are preferably made of metal.

3 are the eye members of the fastening device, which are attached by rivets 4 to

one of the steels, as 1. The eye members 3 have an opening 3' therethrough, with the reduced sized opening 3'' leading out therefrom, in the usual way.

5 are the studs of my improved construction, forming, with the steel 2, the other member of the fastening devices. The studs 5 are of circular shape in cross section, and have short cylindrical necks or stems 5'. The heads 5'' of the studs are made conical or tapering from near the upper ends thereof to the necks or stems 5'.

The cylindrical necks or stems 5' of the studs 5 are of such length, as shown in the drawing, that when the plate steel stud member 2 is covered with fabric, *a*, the exposed portions of said necks or stems will be of a length about equal to the thickness of the slotted eye members 3. From this it results that the slotted eye members will fit closely on the straight or cylindrical necks or stems 5', and close to the bases of the studs, being prevented from working up and down on the studs by the conical heads thereof, when the corset is under tension on the wearer. Thus the steel plate 80 stud member 2 will be so steadily held in place by the co-operative action of the eye members 3 and the studs 5 that said stud member 2 cannot tilt in such a manner as to pinch the flesh of the wearer; while the 85 conical heads of the studs will allow sufficient freedom between the eyes 3 and the studs 5 so that there will be no difficulty in unclasping the corsets. In clasping the corsets the conical heads of the studs will 90 naturally force the eyes 3 down to their proper positions on the cylindrical necks 5' of the studs, as the corsets are placed under tension on the wearer. This will bring the pull on the studs down close to the bases thereof, so as to avoid any tendency to tilt the plate steel stud member 2, as will be understood, and thus avoid danger of pinching the flesh of the wearer, as hereinbefore set forth.

The tapering head 5'' of the stud preferably forms about two-fifths of the length of the stud, and the straight barrel or stem 5' forms about three-fifths of the length of the stud, before it is secured in the opening 105 in the steel.

After the barrel or stem 5' of the stud is inserted in the opening in the steel it is

headed or spread, as shown at 5", Fig. 5, to secure the stud to the steel and hold it in position.

Having thus described my invention, what I claim as new and desire to secure by Letters Patent is:

In a corset fastening, the combination with an eye steel provided with slotted eye members, of a steel stud member provided with studs each having a conical head and

a straight or cylindrical neck, the latter being of a length, when said steel stud member is covered with cloth, approximately equal to the thickness of the said eye members.

AUG. J. LECOUTRE.
